UNITED STATES PATENT OFFICE.

WALTER A. PECK, OF PROVIDENCE, RHODE ISLAND.

MANUFACTURE OF CIGAR-BUNCHES.

SPECIFICATION forming part of Letters Patent No. 451,737, dated May 5, 1891.

Application filed April 5, 1890. Serial No. 346,659. (No model.)

To all whom it may concern:

Be it known that I, WALTER A. PECK, a citizen of the United States, residing at Providence, in the State of Rhode Island, have invented a new and useful Improvement in the Manufacture of Cigar-Bunches, of which the following is a specification.

Heretofore it has been customary in the manufacture of cigar-bunches to take a mass of loose fillers and without giving any definite form or shape thereto roll the binder cylindrically thereon. By this old method the fillers at the ends of the bound bunch are necessarily loose and unconfined, and there is always more or less surplus binder projecting at the ends of the bunch. To properly apply the wrapper to a bunch of this description it has been necessary to first remove the projecting surplus of binder and then to either subject the bunch to the action of a mold to give it the proper form and shape for the cigar to be made therefrom, or else to bring the bunch to the proper form so far as possible during the operation of putting on the wrapper. This latter is a difficult operation, especially in the case of cigars having a pronounced taper at one or both ends, and requires a high degree of skill and careful manipulation on the part of the workman, and, moreover, by such operation an undue strain is liable to be brought upon the wrapper both during the process of applying it and afterward, and to subject the bunches to the action of molds involves time, labor, and expense.

The object of the present invention is to produce a bound cigar-bunch of substantially the form and shape of the cigar to be made therefrom, which said bunch shall be in condition to have the wrapper neatly and smoothly applied thereto without the necessity of subjecting the bunch to the action of a mold and without involving the necessity of the bunch being brought to shape during the process of putting on the wrapper; and to that end the invention relates to a method of forming cigar-bunches, which consists in first shaping the mass of loose fillers into substantially the form of the cigar to be produced and holding said fillers in such form, and then winding the binder spirally thereon in reverse directions, whereby a cigar-bunch

will be produced of substantially the shape of the cigar to be made, and in which the fillers will be firmly held and bound with practically uniform tightness throughout the length of the bunch, including the ends thereof.

In carrying my invention into practice I prefer to make use of a suitable rolling-chamber, of substantially the form of the cigar to be produced, as the most convenient means for giving the desired form and shape to the mass of fillers from which the bunch is to be made. Any other suitable means, however, may be employed for the purpose. When the rolling-chamber is used, a proper quantity of loose fillers is placed in said chamber, and thereby by rolling or otherwise brought into substantially the shape of the cigar to be produced. When the mass of fillers has been brought into the desired shape and while they are held in such shape in the rolling-chamber, the binder is to be wound spirally thereon, as hereinafter described. I prefer to roll the mass of fillers in the rolling-chamber before applying the binder thereto, and thus more thoroughly insure the proper shaping of the mass; but, if desired, the binder may be applied at the commencement of the rolling operation, in which case the shaping of the mass will be sufficiently effected by the shape or form of the chamber itself or by the preliminary turns which necessarily take place in starting the binder thereon.

In putting on the binder, which is preferably of an elongated form, the end of the binder is applied to the mass of fillers intermediate of the ends thereof, and the binder is wound spirally thereon toward that end of the mass which is to form the head or point of the cigar, and then turned upon itself and wound back in a reverse spiral to or toward the opposite end of the mass—that is, the end which is to form the tuck of the cigar, and thereby snugly inclose and firmly bind and hold the fillers in the proper tapering form for the reception of the wrapper. In most cases it will be sufficient to run the binder back to or toward the tuck end of the bunch; but in case cigars with tapering tucks are to be made the binder may, if desired, on reaching the tuck end be again turned upon itself and wound back by a reverse spiral toward the place of beginning, and thus inclose and bind

the tuck end likewise in the proper form. The end of the binder may be secured by paste or in any other suitable manner.

Figure 1 represents a loose unshaped mass of fillers from which the bunch is to be formed for the manufacture of a tapering cigar. Fig. 2 represents a longitudinal section of the cigar-bunch when wound in practically cylindrical form with a projecting surplus of binder, as heretofore in the manufacture of cigars. Fig. 3 represents the mass of fillers shown in Fig. 1 when compactly held in tapering-cigar form to carry out my improved method of manufacture. Fig. 4 represents the same when the binder is first started to wind spirally from the middle portion toward the head end upon the compactly-held fillers. Fig. 5 represents the same when the binder has been wound spirally to the head end and started to return spirally along the body portion of the bunch. Fig. 6 represents the same when the binder has been wound spirally from the head to the tuck and started to return from the tuck to the middle portion. Fig. 7 represents the completely-bound cigar-bunch having the proper tapering-cigar form and without a projecting surplus of binder.

In the accompanying drawings, A, Fig. 1, represents a loose mass of cigar-fillers made of unequal length, and so distributed in the mass that upon the proper compression of the fillers transversely and the application of the binder and the final wrapper thereto a properly-tapered cigar can be made, and in Fig. 2 A' represents the fillers shown in Fig. 1 inclosed in a practically cylindrical form by means of a binder B, as usual in the manufacture of cigars, and leaving in most cases a projecting surplus *a* of binder, which surplus must be carefully removed prior to the application of the final wrapper, the said bunch being tightly bound only at its middle portion, leaving the filler ends *b b* loose and liable to displacement.

In carrying out my improved method of making bunches for the manufacture of tapering cigars I first hold the mass of fillers shown in Fig. 1 in compact tapering-cigar form by any suitable means, as by inclosing the same in the rolling chamber or pocket of

a cigar binding or wrapping machine of proper construction, and then wind the binder, which is made in elongated form, spirally thereon toward and from either of the ends of the compactly-held mass of cigar-fillers.

In Fig. 4 the elongated binder C is represented as being started to wind from the middle portion toward the head end *c* of the filler-bunch, and upon the arrival of the edge *d* of the binder at the head end *c* of the bunch, as shown in Fig. 5, the binder is to be inclined backward to form a reverse spiral from the head end toward the middle portion, as shown in Figs. 5 and 6, and when the edge *e* of the binder has reached the tuck end *f* of the bunch, as shown in Fig. 6, the winding may be either completed in the same direction or the direction of the spiral may be reversed by a backward change in the inclination of the binder and wound to completion in the reverse direction from the tuck *f*, as shown in Fig. 7, thus producing a completed bunch D, in which the fillers are compactly held by the binder at all parts of the bunch in tapered-cigar form and adapted to receive the final wrapper, which, on account of the reverse spiral lapping of the binder and the tightly-held tapering ends of the bunch, will be relieved from the strain due to the elasticity of the compressed fillers and can be wound smoothly upon the bunch to produce the very best grade of work.

I claim as my invention—

1. The method of making cigar-bunches, which consists in first holding the fillers in tapering form at the head end of the bunch and then winding the binders spirally thereon toward and from the head, whereby the fillers will be bound in proper tapering form, as set forth.

2. A cigar-bunch having its mass of fillers tapering toward the head end of the bunch and having a binder wound spirally thereon toward and from the head, whereby the fillers are bound firmly in proper tapering form, substantially as described.

WALTER A. PECK.
